UNITED STATES PATENT OFFICE

SOLOMON LENZNER, OF BUFFALO, NEW YORK

DESIGN FOR A BOTTLE

Application filed July 8, 1932. Serial No. 44,277. Term of patent 7 years.

To all whom it may concern:

Be it known that I, SOLOMON LENZNER, a citizen of the United States, residing at Buffalo, in the county of Erie and State of New York, have invented a new, original, and ornamental Design for Bottles, of which the following is a specification, reference being had to the accompanying drawing, forming a part thereof.

I claim:

The ornamental design for a bottle, substantially as shown.

SOLOMON LENZNER.
